UNITED STATES PATENT OFFICE.

EMIL L. PFUNDER, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 928,882.

Specification of Letters Patent.

Patented July 20, 1909.

Application filed May 5, 1909. Serial No. 494,004.

To all whom it may concern:

Be it known that I, EMIL L. PFUNDER, a citizen of the United States, residing in Hartford, in the county of Hartford and 5 State of Connecticut, have invented certain new and useful Improvements in Type-Writing Machines, of which the following is a specification.

This invention relates to devices usually 10 provided for engaging the side edges of the sheets as they are placed into position for writing.

Heretofore the side gage has been in the form of a ledge turned up from the plate, 15 the latter provided with a claw or hook to fit tightly upon the beaded upper edge of the paper shelf, as in the well known Underwood typewriting machine.

It has been found in practice that these 20 hooks and claws must be so tight, in order to hold the gage properly upon the letter-feeding carriage, that it is difficult to adjust them along the paper shelf, owing to their strong binding action; and moreover the 25 shelf becomes scratched and marred.

The object of this invention is to provide 30 for convenient and easy attachment and detachment of the gage from the paper shelf and easy adjustment therealong, without 35 any liability of marring the appearance of the shelf, and at the same time to provide a very effective means for holding the gage in any position.

According to this invention, a side gage 40 plate is bent up at right angles from a base plate, which overlies the front face of the paper shelf. The upper end of the base plate is curved around the top of the beaded edge of the shelf, and may be provided with a bearing surface of felt or soft material, to prevent marring the shelf. The curved portion of the plate is extended to form a finger-piece. A second plate is hinged upon the main plate, and is also extended to form a 45 companion finger-piece.

Projecting from the second plate is a pair 50 of claws to catch between the edge of the beaded portion of the shelf and the rear face of the shelf. A spring gives the power to grip the shelf.

In the accompanying drawings, Figure 1 is a cross-section of the platen frame of an Underwood typewriting machine, showing how the improved gage is applied to the 55 paper shelf. Fig. 2 is a view similar to Fig.

1, but showing the improved gage applied to the paper shelf. Fig. 3 is a perspective view showing the improved gage in an inverted position.

The usual platen 1 and axle 2 are revolu- 60 bly mounted in a platen frame 3, which includes an inclined paper shelf 4, at the rear of the platen, to support the paper during the operation of the machine, the shelf having its upper edge provided with a rolled or beaded rim 5.

The side gage device comprises a plate 6, bent up from a bottom plate 7, which overlies the front face of the paper shelf 4, the plate 6 serving to gage the edge of the paper as it is 70 inserted between the shelf and platen. The upper end of the plate 7 is curved as at 8, to conform with the beaded end 5 of the shelf 4, and may be provided with a piece of felt or soft material 9; to prevent any marring of the 75 surface of the shelf.

Extending downwardly from the top portion of the plate 7 are two ears 11, between which extends a shaft 12. A plate 14 has a pair of ears 15, projecting upwardly, by 80 means of which the plate is hinged upon the shaft 12. There are also projecting from the plate 14 two claws 16, which engage between the edge of the beaded portion 5 of the shelf 4 and the rear face of the shelf. It is preferred 85 to separate these claws and form them so that they will have a binding or wedging action between the beaded edge and the shelf, to secure a substantial grip, to retain the gage against accidental skewing during the inter- 90 mittent movement of the typewriter carriage. The parts of the claws that bear against the rear of the shelf to produce the wedging or binding action are designated as 95 16^a, and consist of ears bent up from the front edge of the plate 14. The plate 14 is continued rearwardly to form a finger piece 17, and co-operates with a finger piece 10 extended from the curved portion 8 of the plate 7, to form a grip. Springs 13, carried on the 100 shaft 12, engage the finger piece 10 to cause the fingers 16 to press against the shelf to hold the gage in place, as shown in Fig. 2.

To place the gage on the shelf, the finger pieces 10 and 17 are pressed together as 105 shown in Fig. 1, to open the jaws of the clip, and the gage is brought down on the front face of the shelf 4, when the finger pieces may be released and the springs 13 will cause the 110 rocking of the gripping member 14 and cause

the fingers 16 to wedge themselves between the beaded edge and the shelf, as shown in Fig. 2. To adjust the gage along the shelf at any time it is only necessary to press the 5 finger pieces 10 and 17, and slide the gage wherever desired. The gage is very securely held by a resilient gripping means, the adjustment of which is very convenient, and there is no tendency to injure the front 10 face of the shelf.

Having thus described my invention, I claim:

1. A device of the character described, comprising a plate to be secured against the 15 front face of a typewriter shelf and having a part to serve as a paper gage, said plate extending over the upper edge of the shelf and having a finger piece, hinged claws for engaging at the rear of the shelf to hold the gage in 20 place, a spring for forcing said claws into engagement with the shelf, and a companion finger piece carried by said claws.

2. A device of the character described, comprising a plate to be secured against the 25 front face of a typewriter shelf and having a part to serve as a paper gage, said plate extending over the upper edge of the shelf and having a finger piece, hinged claws for engaging at the rear of the shelf to hold the gage in 30 place, a spring for forcing said claws into engagement with the shelf, and a companion

finger piece carried by said claws; said claws formed to wedge between the rolled edge of the shelf and the rear face of the shelf.

3. A device of the character described, comprising a plate to be secured against the front face of a typewriter shelf and having a part to serve as a paper gage, said plate extending over the upper edge of the shelf and having a finger piece, hinged claws for engaging at the rear of the shelf to hold the gage in 35 place, a spring for forcing said claws into engagement with the shelf, and a companion finger piece carried by said claws; said claws formed to wedge between the rolled edge of 40 the shelf and the rear face of the shelf; a facing of soft material being provided upon the under side of said plate to rest upon the beaded edge of the shelf.

4. A device of the character described, comprising a plate to overlie the paper shelf and having a part to serve as a paper gage, said plate extended back over the shelf to form a finger-piece, a companion finger-piece, and means releasable by the companion 45 finger-piece to hold the gage rigidly upon the 50 paper shelf.
